UNITED STATES PATENT OFFICE.

ARLENE P. SANFORD, OF MEDFORD, MASSACHUSETTS.

DESIGN FOR A BABY JACKET.

Application filed September 14, 1925. Serial No. 14,776. Term of patent 14 years.

To all whom it may concern:

Be it known that I, ARLENE P. SANFORD, a citizen of the United States of America, and a resident of Medford, in the county of Middlesex and Commonwealth of Massachusetts, have invented a new, original, and ornamental Design for a Baby Jacket, of which the following is a specification, reference being had to the accompanying drawing, forming part thereof.

I claim:

The ornamental design for a baby jacket as shown.

ARLENE P. SANFORD.
